UNITED STATES PATENT OFFICE

2,546,201

SELF-LOCKING ELECTRICAL CONNECTOR

Lucien Theriault, New Haven, Conn.

Application March 1, 1948, Serial No. 12,227

1 Claim. (Cl. 173—361)

1 The present invention relates to improvements in electrical connectors and relates more particularly to self-locking electrical connectors which are designed and adapted to lock themselves in connected relationship with respect to another electrical fitting so as to avoid accidental disconnection, in the event that undue strain is placed upon the wires or cables to which the electrical connector is attached.

While the self-locking electrical connectors of the present invention are available for many other uses, one of the main uses is in the form of a plug-member having one or more projecting blades or prongs which may form the terminal of one or more conductors leading to portable electrical devices such, for instance, as radios, toasters, heaters, etc.

Numerous so-called "self-locking" electrical connectors have heretofore been designed, substantially all of which are characterized by an operating-member in addition to the body-unit, which operating-member moves relative to the body-unit in order to effect the unlocking of the connector. Such an electrical connector, in improved form, is shown and described in my co-pending application Serial No. 719,049 filed December 28, 1946, which matured into Patent No. 2,498,743 dated February 28, 1950.

I have discovered that it is possible to provide a self-locking electrical connector in which such auxiliary operating-members may be dispensed with and the unlocking action effected solely by means of relative movement between a contact-member and a body-unit which carries the said connector, all in a manner as will be more fully hereinafter described.

One of the main objects of the present invention is to provide a superior self-locking electrical connector characterized by fewness of parts and reliability of operation.

Another object of the present invention is to provide a superior self-locking electrical connector which may be produced at a low cost both with respect to the component parts and the assembly thereof.

A further object of the present invention is to provide a superior self-locking electrical connector which may have its locking-means released by the simple expedient of grasping the body-unit and pulling the same away from such comple-

mental electrical fitting as the connector of the present invention may be attached to.

With the above and other objects in view, as will appear to those skilled in the art from the present disclosure, this invention includes all features in the said disclosure which are not claimed by me in my co-pending application Serial No. 719,049 filed December 28, 1946.

In the accompanying drawings, in which certain modes of carrying out the present invention are shown for illustrative purposes:

Fig. 1 is a view in side elevation of one form of a self-locking electrical connector embodying the principles of the present invention, and shown with the combined contact-and-locking units in their retracted positions relative to the body-unit;

Fig. 2 is an edge view thereof;

Fig. 3 is a view looking toward the inner or 20 blade-end of the connector;

Fig. 4 is a transverse horizontal sectional view taken on the line 4—4 of Fig. 1;

Fig. 5 is a vertical transverse sectional view taken on the line 5—5 of Fig. 1;

Fig. 6 is a vertical sectional view taken on the line 6—6 of Fig. 2, but additionally showing the electrical connector as engaged with and locked to an electrical fitting or outlet;

Fig. 7 is a similar view but showing the body-unit retracted with respect to the combined contact-and-locking units to effect the unlocking of the connector from the complementary electrical outlet;

Fig. 8 is a perspective view of one of the two corresponding body-members, viewing the same mainly from its inner face;

Fig. 9 is a perspective view of one of the combined contact-and-locking units detached and looking toward the outer face thereof;

Fig. 10 is a view similar to Fig. 6 but showing another form which a self-locking electrical connector may assume in accordance with the present invention;

Fig. 11 is a view similar to Fig. 6 but showing the body-unit drawn away from the complementary electrical outlet and also with respect to the contact-and-locking units, to effect the unlocking of the connector;

Fig. 12 is a transverse sectional view taken on the line 12—12 of Fig. 11;

Fig. 13 is a perspective view of one of the two corresponding body-members suitable for use in conjunction with the structure of Figs. 10, 11 and 12;

Fig. 14 is a perspective view of one of the combined contact-and-locking units shown in Figs. 10, 11 and 12; and

Fig. 15 is a similar view but viewing the unit mainly from the opposite direction of the showing of the preceding figure.

The structure of Figs. 1 to 9 inclusive

The particular self-locking electrical connector herein chosen for purposes of illustrating a preferred form of the present invention, is in the form of a double-bladed plug-member of a type designed for connecting floor lamps, radios, toasters, etc., to a source of current supply.

The device illustrated includes a body-unit generally designated by the reference character 10, which is composed of two corresponding juxtaposed body-members respectively designated by the reference characters 11 and 12. The said body-members may be conveniently molded from any suitable insulating material such, for instance, as thermosetting resins, thermoplastic resins, hard rubber and resilient rubber.

Each of the body-members 11 and 12 above referred to has a flat inner race adapted to engage with the similar inner face of the complementary body-member, and each of the said body-members is also formed in its outer race with a recess 13 which is preferably of hexagonal form in cross section. Leading inwardly from the bottom of each recess 13 is a passage 14 registering with the similar passage in the companion body-member and adapted to receive the shank of a coupling-screw 15. The recess 13 in one of the body-members is adapted to receive the head of the coupling-screw 15, while the similar recess of the other body-member is adapted to receive a nut 16, all as is especially well indicated in Fig. 5.

Centrally in its inner end 17, each body-member 12 and 13 is formed with a semicylindrical wire-passage 18 which, when placed in opposition to the similar passage in the complementary body-member, forms a cylindrical passage for a plural-conductor wire, generally designated by the reference character 19.

Each wire-passage 18 communicates at its inner end with a laterally-extending chamber 20 which at its respective opposite ends is in communication with guide-passages 21 and 22. The said guide-passages intersect the substantially-flat outer end 23 of the body-member of which they form features, as is especially well shown in Fig. 8. Formed in the outer portion of each of the guide-passages 21 and 22 is one of two oppositely-sloping cam-surfaces 24-24, for purposes as will hereinafter appear.

To one side of its wire-passage 18, each of the body-members 11 and 12 is formed with an integral locating-stud 25, and on the opposite end of the said passage with a correspondingly-positioned locating-socket 26. Adjacent its outer end 23 and to one side of its longitudinal center, each body-member 11 and 12 is also formed with an integral locating-stud 27, and on the opposite side of its said longitudinal center with a locating-socket 28.

As before explained, each of the body-members 11 and 12 of the body-unit 10 corresponds to each other so that when the said body-members are placed together in face-to-face relationship, the locating-studs 25 and 27 of a given one of the

said body-members will snugly fit respectively into the locating-sockets 26 and 28 in the other body-member, to thus hold the two said body-units against twisting movement relative to each other around the coupling-screw 15 as a center. Furthermore, when the two body-members 11 and 12 are placed in face-to-face relationship, each feature 18 and 20 to 24 inclusive of a given body-member will be in registry with and complement the similar features in the other body-member.

Installed in each of the guide-passages 21 and 22 of the body-members 11 and 12 is one of two corresponding combined contact-and-locking units, generally designated by the reference character 29. Inasmuch as each of the combined contact-and-locking units 29 corresponds to the other, a detailed description of one thereof will serve for both.

In the instance shown, each unit 29 is folded up from sprung sheet metal and comprises a plate-like body 30 which is formed along each of its respective opposite side edges with one of two parallel side flanges 31-31.

Formed integral with and reversely bent from the inner or upper edge of the body 30 is a downwardly-extending locking-arm 32 which is sufficiently narrow to freely fit between the respective opposite side flanges 31-31. The upper or inner portion of each of the locking-arms 32-32 is preferably pressed into tight engagement with the adjacent portion of the body 30 and together therewith is provided with a piercing 33, for purposes as will hereinafter appear. The lower or outer portion of the locking-arm 32 is so set as to normally and resiliently be spaced away from the adjacent portion of the body 30. The projecting lower or outer end of the locking-arm 32 is bent outwardly and slightly upwardly to provide an inclined locking-finger 34, the function of which will hereinafter appear. Each locking-arm 32 is struck outwardly to form a spherically-contoured boss 35 which is adapted to coact with the cam-surfaces 24 previously described.

The side flanges 31-31 of each of the combined contact-and-locking units 29 terminate short of its lower or outer end and the material thereof is bent laterally inwardly from opposite sides to provide complementary resilient fingers 36-36, for purposes of providing a reliable electrical engagement with the contacts of a complementary electrical outlet, in a manner as will more fully hereinafter appear. Centrally of its lower portion, the body 30 is struck up to form a stiffening-rib 37 extending from the outer end of the said body upwardly past the inner or upper edges of the fingers 36-36, as is especially well indicated in Fig. 9.

A given contact-and-locking unit 29, when installed in the body-unit 10, has limited reciprocation lengthwise of the said body-unit, partly in a guide-passage 21 of one body-member and partly in the complementary guide-passage 22 in the other body-member, as is especially well indicated in Figs. 3 and 4. When installed as just described, the outer ends of the said contact-and-locking units will project beyond the outer end 23 of the body-members 11 and 12 so that the locking-fingers 34 will be located well outwardly with respect to the said outer end.

Preferably and as shown in Figs. 6 and 7, the plural-conductor wire 19 has its main insulation or jacket stripped off so that one of the two metal conductors 38-38 thereof, together with its individual insulation, may be extended through the piercing of one of the contact-and-locking units

and then led downwardly toward the outer end of the said unit and there stripped and soldered or otherwise secured in place against the outer face of the flat upper portion of the adjacent locking-arm 32.

The self-locking electrical connector previously described is designed and adapted to be used in conjunction with another electrical connector of any suitable character. The particular complementary electrical outlet or connector indicated in Figs. 6 and 7 of the drawings is one such suitable type and is generally designated by the reference character 39. The said electrical outlet 39 includes a body 40 and a cap 41 suitably secured together and both formed of insulating material. In its upper or outer face, the electrical outlet 39 is formed with a pair of funnel-shaped passages 42-42 spaced from each other a distance which is substantially standard in the art and which corresponds substantially to the spacing of the two contact-and-locking units 29-29. The lower or inner ends of the passages 42-42 respectively lead into chambers 43-43 in the body 40 which respectively accommodate contacts 44-44 which may have any suitable conductors (not shown) connected thereto and leading, for instance, from a source of electrical energy.

The chambers 43-43 in the body 40 of the electrical outlet 39 are larger than the inner or lower ends of the particular funnel-shaped passages 42-42 communicating therewith, with the result that there is provided by the overhanging portions of the said cap, a pair of downwardly-facing locking-abutments 45-45 with which the locking-fingers 34-34 are respectively adapted to engage.

The individual conductors 38-38 of the plural-conductor wire 19 may be secured to the respective contact-and-locking units 29-29 before the said units are assembled between the two body-members 11 and 12.

The coaction of the upper ends of the units 29-29 with the top walls of the lateral chambers 20, and the coaction of the bosses 35 of the said units with the surfaces at the constricted outer ends of the guide-passages 21 and 22, serve to limit the reciprocating movement of the contact-and-locking units with respect to the body-unit 10.

Operation

Let it be assumed that the combined contact-and-locking units 29-29 are retired inwardly with respect to the body-unit 10, as is indicated in Figs. 1 and 2. Under these circumstances, the locking-arms 32-32 will be sprung laterally outwardly relative to the respective bodies 30-30. The assembly may be held by grasping the body-unit 10 and inserting the projecting outer ends of the combined contact-and-locking units 29 respectively into the funnel-shaped passages 42-42 of the electrical outlet 39. During the process of insertion just referred to, the locking-arms 32-32 will be sprung inwardly by the engagement of the sloping outer or under faces of the locking-fingers 34-34 with the surfaces of the cap 41, until the said fingers have been brought into registry with the locking-abutments 45-45, whereupon the said locking-fingers will spring outwardly, in the manner indicated in Fig. 6, to thereby firmly lock the connector of the present invention to the electrical outlet 39.

When the connector of the present invention is assembled with an electrical outlet such as 39 and as is indicated in Fig. 6, any draft exerted upon the plural-conductor wire 19 will be exerted

upon the contact-and-locking units 29-29 and not tend to retract the locking-arms 32-32, since the body-unit 10 will be unaffected. Thus, the connector will remain firmly attached to the electrical outlet 39 despite such strains.

When it is desired to disconnect the connector of the present invention from an outlet such as 39, all that is required is to grasp the body-unit 10 and draw the same away from the electrical outlet 39 to thereby move the said body-unit relative to the contact-and-locking units 29-29. The movement just referred to will cause the cam-surfaces 24-24 to press inwardly upon the bosses 35-35 of the respective units 29-29 to thereby bring the locking-fingers 34-34 out of locking relationship with respect to the locking-abutments 45-45 of the electrical outlet 39, all as is indicated in Fig. 7.

The structure of Figs. 10 to 15 inclusive

The self-locking electrical connector previously described has its locking-fingers 34-34 yieldingly urged outwardly into their locking positions by the tensions of the respective locking-arms 32-32, with the said locking-fingers being positively retired into their unlocking positions.

The self-locking electrical connector of Figs. 10 to 15 inclusive provides for the positive movement of locking-fingers (similar to the previously-described locking-fingers 34) into both their locking and unlocking positions, all in a manner as will be presently described.

The self-locking electrical connector of Figs. 10 to 15 inclusive includes a body-unit generally designated by the reference character 46 and composed of two corresponding abutting-members respectively designated by the reference characters 47 and 48. The said body-members are generally similar to the body-members 11 and 12 previously described and may be secured together in a like manner.

Each of the body-members 47 and 48 is formed centrally in its inner end 49 with a semicylindrical wire-passage 50 which, when placed in opposition to the similar passage in the complementary body-member, forms a cylindrical passage for a plural-conductor wire generally designated by the reference character 51.

Each wire-passage 50 communicates with a laterally-extending chamber 52 which is in communication at its respective opposite ends with one of two similar guide-passages 53-53. Formed in the outer portion of each of the guide-passages 53-53 is one of two oppositely-sloping releasing cam-surfaces 54-54. Also formed in the outer portion of each of the guide-passages 53-53 is one of two oppositely-sloping locking cam-surfaces 55-55.

The oppositely-sloping locking cam-surfaces 55-55 above referred to respectively constitute the sloping upper walls of two notch-like clearance-recesses 56-56 and each terminates in one of two dwells 57-57 extending in substantial parallelism with the longitudinal axis of the body-unit 46.

Installed in each aligned pair of the guide-passages 53-53 of the complementary body-members 47 and 48, is one of two corresponding combined contact-and-locking units, each generally designated by the reference character 58. Each contact-and-locking unit 58 is folded up from springy sheet metal and comprises a plate-like body 59 and a downwardly-extending resilient locking-arm 60.

The body 59 of each of the contact-and-lock-

ing units 58—58 is formed along each of its respective opposite side edges with one of two parallel side-flanges 61—61 receiving between them the locking-arm 60 before referred to. The extreme lower or outer end of each of the contact-and-locking units 58—58 is reversely bent upon itself to provide a resilient finger 62.

The upper or inner ends of each body 59 and its adjacent locking-arm 60 are integrally united and both thereof are formed adjacent their inner ends with piercings 63 through which one of the two metal conductors 64—64 of the plural-conductor wire 51 may be passed for being soldered in place, as is indicated in Figs. 10 and 11.

About midway of its length and adjacent each of its side edges, each locking-arm 60—60 is struck up to provide two laterally-spaced-apart loop-like bosses 65—65 which are adapted to contact with the adjacent releasing cam-surfaces 54—54 in a manner as will hereinafter appear. Laterally intermediate the loop-like bosses 65—65, each locking-arm 60 is deformed to provide a loop-like boss 66 which is adapted to move freely in a clearance-opening 67 formed in the adjacent portion of the body 59. The said boss 66 is adapted to be accommodated in the adjacent pair of clearance-recesses 56 and to coat with the adjacent pair of locking cam-surfaces 55—55, as well as with the adjacent pair of dwells 57—57.

The extreme outer end of each of the locking-arms 60—60 is bent laterally outwardly to provide it with a locking-finger or -projection 68 similar to the locking-fingers 34 previously described.

The self-locking electrical connector of Figs. 10 to 15 inclusive is, like the connector previously described, designed and adapted to be used in conjunction with another electrical connector of any suitable character. In this particular instance, it may be assumed that the complementary electrical outlet or connector is of the same character as the electrical outlet 39 previously described and portions of which are shown in both Figs. 10 and 11.

Operation

Let it be assumed that the self-locking electrical connector now being described is in coupled relationship with an electrical outlet 39, as is shown in Fig. 10. To effect such connection, the normal procedure would be for the user to grasp the connector by means of its body-unit 46 and insert the projecting outer ends of the contact-and-locking units 58—58 into the respective funnel-shaped passages 42—42 in the cap 41. Such insertion will encounter frictional resistance with the result that the body-unit 46 will move downwardly with respect to the contact-and-locking units 58—58, thus causing the locking cam-surfaces 55 to act on the boss 66 of each locking-arm 60 to cam the said locking-arm laterally outwardly toward the position in which it is shown in Fig. 10. Each boss 66 will ultimately come to rest upon the adjacent pair of dwells 57 to thus cause each locking-arm 60 to be maintained in an outwardly fixed position wherein its complementary locking-finger 68 is in position to engage with the adjacent locking-abutments 45 of the electrical outlet 39. Each locking-arm 60—60 is preferably so tensioned as to tend to lie flat against the adjacent face of its complementary body 59.

It will thus be clear that when the self-locking electrical connector is connected, as shown in Fig. 10, to the electrical outlet 39, any draft

upon the plural-conductor wire 51 will be resisted by the locking-fingers 68—68 and the complementary locking-abutments 45—45 of the outlet 39.

When it is desired to disconnect the self-locking electrical connector from the electrical outlet 39 or the like, the user may grasp the body-unit 46 thereof and draw the same away from the electrical outlet 39. This action will move the said body-unit outwardly with respect to the contact-and-locking units 58—58 until its clearance-recesses 56 register with the loop-like bosses 66. When the body-unit moves outwardly, as described, the releasing cam-surfaces 54—54 engage with the loop-like bosses 65—65 to thus positively force the locking-arms 60—60 inwardly into locking positions, in the event that the said locking-arms do not so move under their own inherent tension. The parts will now have assumed the positions in which they are shown in Fig. 11, following which the self-locking electrical connector now under discussion may be completely removed from association with the electrical outlet 39.

Résumé

From the foregoing it will be apparent that both of the illustrated and described forms of the present invention are characterized by having one or more combined contact-and-locking units mounted with respect to the body-unit with freedom for limited lengthwise or floating movement. Furthermore, each of the forms of the present invention illustrated and described is characterized by the fact that the relative movement between the body-unit and one or more contact-and-locking units provides for the unlocking of the device from a complementary electrical outlet without requiring the employment of auxiliary operating features such, for instance, as releasing finger-buttons or other separate operating-means movable with respect to the body-unit.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

I claim:

A self-locking electrical connector, including in combination: a body-unit having a guide-passage therein receiving and guiding the lengthwise reciprocation of the hereinafter-mentioned combined contact-and-locking unit, the said guide-passage opening at one end through the exterior of the body-unit, the said body-unit also being provided in one lateral wall of its said guide-passage with a fixed actuating-abutment; and an elongate combined contact-and-locking unit mounted for lengthwise reciprocation in the guide-passage of the said body-unit, the said contact-and-locking unit comprising a contact-portion and a resilient locking-arm extending in substantial parallelism with and flexible laterally toward and away from the said contact-portion for movement into and out of locking engagement with a complementary electrical receptacle, both the said contact-portion and the said locking-arm projecting outwardly beyond the said body-unit, the said resilient locking-arm having a laterally-extending locking-finger at its projecting portion and also having an actuating-abutment constructed and arranged to engage

with the said fixed actuating-abutment in the lateral wall of the said guide-passage and constructed and arranged to jointly therewith flex the said resilient locking-arm laterally relative to the said contact-portion to shift the said locking-finger when the said combined contact-and-locking unit and the said body-unit are moved with respect to each other in a direction lengthwise of the said contact-and-locking unit.
